United States Patent Office

Des. 210,452
Patented Mar. 12, 1968

210,452

CHAIR

John D. Beinert, Babylon, N.Y., assignor to Spiegel
Industries Corp., Teaneck, N.J., a corporation of
New Jersey

Filed Mar. 13, 1967, Ser. No. 6,206

Term of patent 14 years

(Cl. D15—1)

FIG.4

FIG. 1 is a perspective view of a chair showing my new design;

FIG. 2 is a front view of said chair which is on a reduced scale;

FIG. 3 is a top plan view of FIG. 2;

FIG. 4 is a side view of FIG. 2; and

FIG. 5 is a section taken at line 5—5 in FIG. 4.

The back of the chair is conventionally plain.

I claim:

The ornamental design for a chair, substantially as shown and described.
